DESIGN FOR A SCARF OR SIMILAR ARTICLE

Joseph Abouchar, New York, N. Y.

Application September 30, 1936, Serial No. 65,083

Term of patent 3½ years

To all whom it may concern:

Be it known that I, Joseph Abouchar, a citizen of the United States of America, residing in city of New York, county of New York, and State of New York, have invented a new, original, and ornamental Design for a Scarf or Similar Article, of which the following is a specification, reference being had to the accompanying drawing, forming part thereof.

The figure is a face view of a quarter section of a scarf or similar article showing my new design, the other three sections being identical with that here disclosed, arranged in proper relation to complete the scarf or similar article.

I claim:

The ornamental design for a scarf or similar article substantially as shown and described.

JOSEPH ABOUCHAR.
